UNITED STATES PATENT OFFICE

JOHN C. TAYLOR, OF ANACONDA, MONTANA

ATTACHMENT FOR PENCILS

Application filed March 30, 1928. Serial No. 265,945.

This invention relates to cutter attachments for mechanical pencils.

A primary object of the invention is to provide a cutter which may either constitute 5 a part of the main chamber, or be used merely as an attachment for the pencil.

Another object of the invention is to so construct a device of this character that it may be used for scraping, cutting, for clipping bills of ladings from boxes, packages, 10 and the like, and for many other purposes.

Another object of the invention is to provide a device of this character, the blade of 15 which is formed as a unitary structure with the mounting.

In carrying out these objects, the invention is susceptible of a wide range of modification without departing from the spirit or sacrificing any of the advantages of the claimed 20 invention; there being shown in the drawings for illustrative purposes a preferred and practical form, in which;

Figure 1 represents a perspective view of 25 a mechanical pencil equipped with this improved attachment, and

Fig. 2 is a side elevation of a pencil with the attachment shown in longitudinal section.

In the embodiment illustrated, a mechanical pencil 1, is shown having a hollow detachable metallic end portion 2 which in these figures is shown threaded onto the tubular nib 3. This portion 2 has its outer end flattened to provide a cutting or scraping 35 blade 4, said blade being here shown arranged at an obtuse angle to the body portion 2, although obviously it may be in alignment therewith if found desirable to do so. The terminal of this blade 4 is shown tapered to 40 provide an entrance point 5. This blade 4 as shown is substantially triangular in form, although obviously, it may be of any desired shape, and the edges thereof may be sharpened or not, as desired. By arranging the 45 blade 4 at an angle, it may be more conveniently used as a scraper.

It will be obvious that this attachment may be composed of any suitable metal, aluminum being preferably used, since it is lighter and 50 does not corrode.

The mounting of this attachment on a pencil provides a very handy article particularly useful for expressmen in stripping off waybills and in making corrections and changes in the addresses, necessary to complete the bill. 55

Without further description it is thought that the features and advantages of the invention will be readily apparent to those skilled in the art, and it will of course, be 60 understood that changes in the form, proportion and minor details of construction may be resorted to, without departing from the spirit of the invention or its scope as claimed.

I claim:—

1. An attachment for lead pencils comprising a hollow metal body having one end extended longitudinally, flattened to bring the opposed walls thereof into contact, said flattened portion being sharpened, to provide a 70 scraping or cutting blade. 65

2. An attachment for lead pencils, comprising a hollow metal tubular body with one end flattened with the edges of said flattened portion contacting along a diametral line of 75 said hollow metal tubular body, and being sharpened to provide a cutting blade, said blade being bent transversely at its inner end at an angle to the body and being tapered outwardly from said inner end to facilitate its use as a scraper. 80
